UNITED STATES PATENT OFFICE.

ROBERT H. JEFFREY, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,313,993.

Specification of Letters Patent. Patented Aug. 26, 1919.

Application filed May 1, 1914, Serial No. 335,758. Renewed December 28, 1918. Serial No. 268,703.

To all whom it may concern:

Be it known that I, ROBERT H. JEFFREY, a citizen of the United States, residing at Columbus, in the county of Franklin and State of Ohio, have invented certain new and useful Improvements in Mining-Machines, of which the following is a specification, reference being had thereto to the accompanying drawing.

10 The invention relates more especially to mining machines of the side cutting type, and has for its object to effect the horizontal cutting of the coal primarily by multiple, parallel kerf cutters which may produce not only narrow kerfs in the body of the coal, but kerfs of relatively great horizontal extent, whereby comparatively little of the coal in proportion to the extent of the cut may be wasted in the process; also to provide various improvements in the mechanism whereby it is rendered more simple, convenient and effective for the purpose.

In order to make the invention more clearly understood there are shown in the accompanying drawings means for carrying the same into practical effect, without limiting the improvements, in their useful applications, to the particular construction which, for the purpose of explanation, has been delineated; and with the understanding that the invention may be embodied in other forms of construction. In the said drawings—

Figure 1 is a plan view of a mining machine embodying the invention, the front or inner portion of the same being shown in dotted lines.

Fig. 2 is a side elevation of the same, showing the coal face in vertical section and the cutters entered therein to nearly the full extent.

Referring to the drawings, 1 is the bottom plate of the bed frame, the latter having also flanged side plates 2 and a top plate 3, all of which are connected to form a rigid structure. The top plate 3 is preferably in the form of a casting upon which the cutter frame is mounted. The cutter frame is composed of top and bottom side plates 6 and 7, with interposed vertical plates, the whole being united by rivets into a rigid structure. In this structure are comprised upper and lower end plates 11 and 12, by which the side plates 6, 7 are united at their front ends. At their rear ends they are attached

to the bed frame. The plates 6, 7 and 11, 12 are arranged to leave between them at their outer sides guide spaces for the cutter and drive chain 10. The latter may be of any suitable construction to operate the bits or cutters 10', and to drive the multiple kerf cutters as hereinafter described.

At the outer end of the cutter frame the cutter chain passes over a sprocket wheel 14 which is loosely mounted on a fixed vertical shaft on the rear or outer part of the bed frame.

The machine is or may be propelled along the face of the coal during the cutting operation by a cable or the like, and upon the inner end of the bed frame is mounted a winding drum 18. A suitable draft cable 19 has one end secured to the winding drum so that it can be wound upon the drum when the latter is turned. The cable 19 passes downward from the drum and under a guide sheave or pulley 17 mounted in a castor block or frame 16 having a tubular spindle rotatably mounted in the top plate of the bed frame. The arrangement is such that the cable 19 passes downward through said spindle and under the pulley. The cable can be taken off in any desired direction within a range of about 180°, either toward the face of the coal when the machine is to be fed inward at the right rib to make the sumping cut, or away from the machine along the face of the coal to the left rib when the feed is to be parallel, or substantially so, with the coal face. For any such directions of feed the cutter end of the cable is anchored by a jack or in other known manner.

The drum 18 is mounted upon a longitudinally disposed shaft 20 mounted in bearings 21, 22.

27 is an electric motor of any preferred construction, which is mounted upon the outer end of the bed frame with its armature shaft 28 arranged longitudinally of the machine to drive the drum 18 and the chain 10. The shaft 28 carries at its inner end a bevel pinion 29 which meshes with a bevel gear 30 fixed on the vertical shaft 31. The lower end of this shaft is mounted in a bearing 32 attached to the bed frame. The upper end of the shaft turns in a bearing 33 carried by a yoke 34 mounted on the bed frame. 35 is a worm fixed on the shaft 31 and meshing with a worm wheel 36 fixed on a longitudinal shaft 37. This shaft is 110

- mounted in turn in bearings 38, 39 fixed on the top plate of the bed frame. A bail bearing 39' may be applied between the gear 30 and its bearing 33 to take the end thrust of the worm. 41 is a pinion loose on the shaft 37, and on the inner end of the shaft is loosely mounted a sleeve 42', which turns in the bearing 38. 42 is a pinion fixed on the inner end of the sleeve 42', and 43 is a large spur gear fixed on its outer end. The gear 43 has an outer clutch face or extension 44 and the pinion 41 has an inner clutch member 45. 46 is a double clutch member slidably keyed on the shaft 37 and engageable at will with either of the clutch elements 44 or 45 by means of a shifting hand lever 49 and suitable connections.
- The pinion 41 meshes with a gear wheel 50 which is fixed on the outer end of a short shaft 51 turnable in a bearing 52 on the bed frame. 53 is a pinion secured on the inner end of the shaft 51 and meshing with the gear wheel 43. The pinion 42 meshes with a large gear 54 fixed on the drum 18, or on its shaft. 55 is the ball thrust bearing interposed between the pinion 41 and the outer bearing 39 to take the end thrust of the shaft 37. The gearing is preferably enclosed by a casing 68.
- 30 By the gearing described the drum 18 can be driven at either of two speeds from the motor and shaft 31. Thus, if the clutch member 46 is thrown so as to make the pinion 41 fast on the shaft 37 the latter will 35 turn the shaft 51 through the gear 50 and the drum 18 through the pinion 53, gear 43, sleeve 42', pinion 42 and gear 54, and at a lower speed. If the clutch be caused to connect the shaft 37 directly with the gear 40 43 the drum 18 will be turned in the same direction as before, but at a higher speed, through the sleeve 42' and its said driven connections, the pinion 53, gear 50 and pinion 41 turning idly.
- 45 The cutter chain wheel 14 is connectible at will by a clutch device 59 with a gear 57 on its shaft, and this gear is driven by a pinion 56 fixed on the lower end of the motor-driven shaft 31.
- 50 To retard the outer end of the machine as against the pull of the cable 19 and keep it directed at the desired angle to the coal face, an unwinding drum 73 and cable 74 are provided. The outer end of the cable 55 is suitably anchored at the right rib and the drum is yieldably held as it unwinds by an adjustable friction brake band or device 75, so that the outer end of the machine is allowed to move to the left only about as 60 fast as do the cutting devices, as the machine is fed by the cable 19.
- The parts above described are or may be of the construction shown in the patent of Edwin R. Merrill, No. 1,127,663 granted 75 Feb. 9, 1915.

76 is a rotary cutter shaft extended upward from the chain cutter. It is or may be substantially vertical. Its lower end passes through a bearing 77 fixed on the cutter frame plate 11 and attached to said lower end is a driving means such as a chain wheel 78 arranged between the plates 11 and 12. The hub 84 of the wheel 78 fits as a journal of large diameter within the bearing 77. The chain 10 engages and rotates the wheel 78 and cutter shaft 76. The upper part of the shaft 76, or a sleeve thereon, is mounted in a bearing 79 which is carried by bracket arms 80 attached to the cutter frame plates 6.

80 81 indicates a kerf cutter or narrow saw, a plurality or series of which, parallel with each other, are fixed or clamped on the shaft 76, as by spacing sleeve elements 82, washers 83 and one or more nuts 84. The shaft 85 may be extended above the bearing 79 and carry one or more cutters 81 above such bearing.

85 It is not necessary that the chain cutting mechanism 10, 10', make a complete undercut as deep as the kerfs, provided it make sufficient cut, as may be necessary, for the introduction of the cutter shaft driving wheel 78, or other driving means, partly 90 within the coal face, so that the cutters 95 81 may enter up to their hubs and make as deep a cut and advance into and along the coal face as possible. By an arrangement, such as is illustrated (Fig. 2), the kerf cutters may cut and enter and thereafter be fed considerably in advance of the chain or under cutter. It results from this that in the sumping cut the kerf cutters or saws may or do enter the coal face for one half or more of their total depth of cut 100 before the chain or under cutter begins to act, except as a driving element for the kerf cutters; and during the subsequent kerf-forming operation across the face of the coal the chain or under cutter operates on, 105 cuts and removes much less coal than it would if it entered to the same depth as the kerf cutters. The machine consequently requires much less power both in sumping and in kerf cutting, and can be fed at materially greater speed.

110 During the sumping cut the guiding of the machine may be aided by a guiding means 86 attached to the floor as set forth in said Merrill patent. As the side cut nears 115 completion the brake device 75 is tightened, causing the cutters to be swung more to the left to cut into the corner.

120 The bearing 77 may act as a guide, by its contact with the coal face, during the movement of the machine across the face of the coal.

What I claim is:

1. In a mining machine, the combination of narrow kerf cutters arranged parallel and 130

- in multiple, a chain cutter arranged as an undercutter below said kerf cutters, and a shaft carrying all of said cutters whereby the said chain cutter drives the said kerf cutters; substantially as set forth. 5
2. In a mining machine, the combination of kerf cutting saws arranged parallel and in multiple, a chain cutter arranged as an undercutter below said saws and a shaft carrying all of said cutters whereby the said chain cutter rotates the said saws; substantially as set forth. 10
3. In a mining machine, the combination of kerf cutters arranged parallel and in multiple, a chain cutter arranged as an undercutter below said kerf cutters, a shaft carrying all of said cutters whereby the said chain cutter drives the said kerf cutters, and means for feeding the kerf cutters and 15 chain cutter together bodily across the face of the coal; substantially as set forth. 20
4. In a mining machine, the combination of kerf cutting saws arranged parallel and in multiple, a chain cutter arranged as an undercutter below said saws, a shaft carrying all of said cutters whereby the said chain cutter rotates the saws, and means for feeding the saws and the chain cutter together bodily across the face of the coal; substantially as set forth. 25
5. In a mining machine, the combination of narrow kerf cutters arranged parallel and in multiple, and an undercutter arranged to cut a thick or wide kerf below the narrow kerfs; said multiple kerf cutters being extended forward of said undercutter and adapted to cut into the coal beyond the cut of the latter; substantially as set forth. 30
6. In a mining machine, the combination of a bed frame, a chain cutter frame carried thereby, a vertical shaft mounted at its bottom end on said cutter frame, kerf cutters fixed on the upper part of said shaft, an under cutting chain mounted at its forward 35
- part on the bottom end of said shaft to drive 45 the same, and means for feeding the bed frame laterally across the face of the coal. 50
7. In a mining machine, the combination of a bed frame, a chain cutter carried at the inner end of the same, narrow kerf cutting saws arranged horizontally in multiple above the chain cutter and adapted to cut into the coal beyond the cut of the chain cutter, and means for actuating the said cutter and saws; substantially as set forth. 55
8. In a mining machine, the combination of a bed frame, a motor thereon, a chain cutter frame fixed to and extending from the inner end of the bed frame, a vertical shaft mounted above the chain cutter frame, horizontal narrow kerf cutters arranged parallel and in multiple on the said vertical shaft, a chain cutter on the said cutter frame, means whereby the chain cutter rotates the said shaft, and driving mechanism connecting 60 the motor with the chain cutter; substantially as set forth. 65
9. In a mining machine, the combination of a bed frame, a cutter frame attached to the inner end of the bed frame, a chain cutter mounted and operating on the said cutter frame, a lower bearing supported on the cutter frame, an upper bearing having means whereby it is supported at a distance above the cutter frame, a vertical shaft 70 mounted in the said bearings, narrow kerf cutting saws fixed on the said shaft, means whereby the chain cutter actuates the said shaft, and means for feeding the bed frame across the face of the coal; substantially as 75 set forth. 80

In testimony whereof, I affix my signature, in presence of two witnesses.

ROBERT H. JEFFREY.
